UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

WATER-COOLED FLOOR STRUCTURE.

1,223,801.

Specification of Letters Patent. Patented Apr. 24, 1917.

Original application filed October 24, 1914, Serial No. 868,544. Divided and this application filed March 4, 1915. Serial No. 82,192.

To all whom it may concern:

Be it known that I, LUTHER L. KNOX, a citizen of the United States, residing at Avalon, in the county of Allegheny and State of Pennsylvania, have invented a new and useful Improvement in Water-Cooled Floor Structures, of which the following is a full, clear, and exact description, reference being had to the accompanying drawings, forming part of this specification, in which—

Figure 1 is a plan view partly broken away of a floor structure embodying my invention;

Fig. 2 is a section on the line II—II of Fig. 1;

Fig. 2^a is a fragmentary sectional view; and

Figs. 3, 4 and 5 are views similar to Fig. 2, but showing three different modifications.

My invention has relation to water-cooled floors and is designed to provide water-cooled floors or platforms for use around furnaces and the like; and is also designed to provide a floor of this character which can be manufactured at relatively low cost, which can be readily placed in position, and which is strong and durable.

Referring first to that form of my invention shown in Figs. 1, 2 and 2^a:

The floor structure shown in Fig. 1 is composed of two similar sections or units placed side by side. It will be understood that any number of these units may be employed according to the desired area, and that they may be of similar or different shapes according to the shape of the space into which they are to be fitted. 2 and 3 designate water-circulating connections for the structure, and 4 a circulating connection between the two units.

The water-cooled portion of the structure comprises a floor plate 5 of relatively thick metal, to which is secured a bottom plate member 6, preferably formed of sheet metal shaped to form, with the floor plate, a plurality of water-containing and circulating chambers 7. In the construction shown in these figures, the member 6 has a central rib portion 8, pressed upwardly therein and which is riveted to the floor plate at 9. The edge portions of the member 6 are flanged upwardly and thence outwardly, and the

outwardly turned flanges 10 are riveted to the floor plate 5 at 10^a. The lateral edge portions of the floor plate beyond the edges of the member 6 are riveted to the flanges of I-beams 11. The adjacent sections of the floor abut each other on the I-beams, the adjacent edges of the units being secured to opposite flanges of the same beam.

The ribs 8 also act as baffles to provide for a back and forth circulation of the water through the section; and for thus purpose, these ribs are formed at one end with depressions 12, shown in Fig. 1, and also in detail in Fig. 2^a, such depressions acting as connecting channels between the opposite sides of the baffles.

The construction shown in Fig. 3 is similar to that just described, except that instead of a single bottom plate member 6, I provide a separate bottom plate member 6^a, whose flanged edge portions 9^a are secured to the floor plate 5^a. In this form of the invention, I also provide an intermediate I-beam 11^a, which supports the floor plate between the two water-containing and circulating chambers 7^a. It will be understood that each section may be provided with more than two water-circulating chambers 7^a, with as many of the intermediate beams 11^a as are necessary.

The construction shown in Fig. 4 is similar to that shown in Fig. 3, except that instead of turning outwardly the upwardly flanged edges of the bottom members 6^b, the upper edges of the vertical flanges are welded at 13 to the underside of the floor plate 5^b.

In the construction shown in Fig. 5, the bottom members 6^c between each of the intermediate I-beams 11^c have their lateral edges downwardly flanged, as indicated at 14, and these flanges are riveted to the webs of the I-beams at 15. In this construction, the upper portions of the webs of the I-beams form the baffles between adjacent chambers 7^c, and holes may be cut through these webs at any desired points, to provide circulating communications between adjacent chambers. Instead of using complete I-beams, I may use beams composed of two separate channels 16, placed back to back, as indicated at the right-hand end of Fig. 5, which illustrates the connection between two adjacent floor sections.

My invention provides a construction which can be readily manufactured and secured to supporting beams or in which the supporting beams may form a part of the structure itself. The invention is susceptible of various other modifications within the scope of the appended claims.

The present application is a division of my pending application, Serial No. 868,544, filed October 24, 1914.

I claim:

1. A water-cooled floor structure, comprising substantially parallel flanged beam members, a floor plate secured to the upper flange 15 of said beam members, and flanged bottom plate members between the beams and forming with said floor plate a series of hollow water-containing spaces, substantially as described.
2. A water-cooled floor structure, comprising substantially parallel flanged beam members, a floor plate secured to the upper flange of said beam members, and flanged bottom plate members between the beams 25 and forming with said floor plate a series of hollow water-containing spaces, there being water-circulating connections between the spaces, substantially as described.
3. A water-cooled floor comprising a floor 30 plate, a plurality of flanged bottom members secured to said plate and forming with the plate a plurality of water-containing chambers, and supporting beams secured to

the floor plate, some of said beams being between adjacent chambers, substantially as 35 described.

4. A water-cooled floor comprising a floor plate, a plurality of flanged bottom members secured to said plate and forming with the plate a plurality of water-containing chambers, and supporting beams secured to the floor plate, some of said beams being between adjacent chambers, said beams forming a structural part of the structure, substantially as described. 45

5. A water-cooled floor comprising a floor plate, a plurality of bottom plate members having flanged edges, and a plurality of beams having a web portion and upper flanges to which the floor plates are secured, 50 the flanged edges of the bottom plate members being secured to the web portions of said beams, substantially as described.

6. A water cooled floor structure, comprising a plurality of floor supporting members, 55 a floor plate supported thereon, and flanged bottom plate members between the supporting members forming with said floor plate a series of hollow water containing spaces; substantially as described.

In testimony whereof, I have hereunto set my hand.

LUTHER L. KNOX.
